ROOF TRUSS

John S. Edison, Los Angeles, Calif., assignor to
 Wm. P. Neil Company, Ltd., Los Angeles, Calif.,
 a corporation of California

Application September 15, 1936, Serial No. 100,887

10 Claims. (Cl. 108—23)

My invention relates to roof trusses and particularly to the timber trusses commonly known as the bowstring type.

One of the principal objects of this invention is to provide a novel shoe for rigidly and economically securing together the coincident ends of the upper arched and lower chords of a truss, and to provide such a shoe which is simple and economical to fabricate.

Another important object of this invention is the provision in connection with such a shoe of simple means for fastening the truss to a wall or column, and also for anchoring horizontal angle braces.

A further important object is the provision of a novel and simple method of fabrication of the upper chord of a timber bow-string type of truss.

Another object of this invention is to provide a novel and simple method of securing the upper ends of diagonal braces to the secured or abutted ends of the sections of the upper chord.

With these and other objects in view, as will appear hereinafter, I have devised a roof truss having certain novel features of construction, combination, and arrangement of parts and portions, as will be hereinafter described in detail and particularly set forth in the appended claims, reference being had to the accompanying drawings and to the characters of reference thereon which form a part of this application, in which:

Fig. 1 is a fragmentary side elevation of a roof truss embodying my invention in one form;

Fig. 2 is a sectional elevation thereof taken through 2—2 of Fig. 1;

Fig. 3 is a plan view of the shoe for the truss;

Fig. 4 is a fragmentary perspective view of the truss;

Figs. 5, 6, and 7 are views similar to Figs. 1, 2, and 3 of a slightly modified form of my truss.

In Figs. 1, 2, 3, and 4, the lower chord 1 and the arched upper chord 2 are each made of spaced apart timbers, such as 2 inch planks, placed on edge, the elements of the former being designated 1^a and of the latter 2^a. These chords are

supported relative to each other by vertical cross braces 3 and diagonal braces 4. These braces, in most instances, are secured with their ends between the spaced apart elements or timbers of which the chords are made; that is, the chord elements are spaced apart the thickness of the braces.

The coincident ends of the chords or chord members are secured together by end members or shoes 11. Each shoe, in this instance, consists essentially of an end plate 12 and a pair of spaced

apart web members 13. The end plate consists of a horizontal or base plate 12^a having an upwardly bent or right angle portion or flange 12^b at its outer edge, and at the upper edge of the latter a relatively narrow flange 12^c which extends upwardly, at an acute angle, over the base plate. That is, the plate 12^c, which serves as a retaining plate, is spaced above the base plate, and these two plates are joined at their coincident edges by the portion or plate 12^b. The web members or plates are placed on edge and perpendicular to the base plate 12^a and flange 12^b and extend horizontally a considerable distance beyond the base plate. They are of substantially the width of or slightly less than the chord elements 1^a, and the outside width of the spaced apart plates is substantially equal to the space between the chord elements 1^a so as to fill the space therebetween.

The base plate 12^a is provided with holes 12^d for securing the truss to an abutment, wall, or column. This plate is provided with other holes 12^e forwardly thereof, that is, in the portion normally extending beyond the wall, for attaching horizontal cross braces.

Between the web plates 13 is located a filler 14, preferably of wood.

The web plates 13 extend through and beyond the joined portions of the plates 12^a and 12^c, that is, through and beyond the joining portion which, in this instance, is the vertical plate or flange 12^b. These web plates extend preferably through spaced vertical slots in the vertical flange 12^b and are bent in opposite directions against the outer side of said flange 12^b, as indicated by 12^f. These bent over portions 12^f may be secured to the flange 12^b by rivets 16 or by welding, or both. The lower edges of the web plates are preferably welded to the base plate.

At the top of the chord is a cap plate 21, in the form of a 2 inch plank, which extends over both chord elements 2^a and is wider than the overall width of both, as shown in Fig. 2.

The end of the upper chord, consisting of the elements 2^a and the cap plate 21, is seated in the end member or shoe 11, being butted with its end against the base plate 12^a and the vertical flange 12^b and with the cap plate retained by and engaging the underside of the flange 12^c.

The ends of the lower chord elements 1^a are bevelled at 1^b and fitted against the under edge of the elements 2^a. The ends of the lower edges of the latter rest on the base plate 12^a as shown in Figs. 1 and 4.

At the opposite sides and over the joint or

55

splice between the ends of the chord members is provided preferably an angular plate of structural ply-wood 26.

5 The angular plates 26, and chord elements 1^a and 2^a are secured together and to the web of the shoe by bolts 15, as shown.

10 The arched upper chord member 2 consists of a plurality of sections, namely, end sections 2^b, and intermediate sections 2^c and 2^d. All sections 15 are made up of spaced apart chord elements 2^a. The elements of the end sections 2^b are straight timbers or planks with straight top and bottom edges. The top edges of the center section 2^d and the other sections 2^c, between the center and 20 end sections, are curved as shown. This method of constructing the upper chord presents an appearance very similar to the conventional bow-string truss, has substantially the same load carrying capacity, and is considerably more economical to make.

25 The several sections of the upper chord are spliced together by filler members 31, each half being secured between the elements of the adjacent and abutting sections. The several members are bolted together substantially as shown.

30 The upper ends of the vertical braces 3 abut against the under side of median portions of the filler members, and are secured in place by metal straps 32 which extend around the filler members and the opposite sides of the braces, as shown.

35 The modified structure, shown in Figs. 5, 6, and 7 is similar in construction, in most respects, except that the chord elements 1^a and 2^a are placed against each other and the cross braces 3 and 4 are secured to the outer sides of said chord elements. The shoe 11 is also modified in that the plates of the web 13 are placed together, as shown in Fig. 7. With this construction, the chord elements are slightly separated at their 40 ends so as to receive the web plates.

If desired, the web 13, in this modification, may consist of a single plate, welded at its lower edge and end to the plate 12 of the shoe.

45 Though I have shown and described a particular construction, and certain modifications thereof, I do not wish to be limited to the same, but desire to include in the scope of my invention the construction, combination, and arrangement substantially as set forth in the appended claims.

50 I claim:

1. In a roof truss, a shoe for the truss consisting of a horizontal plate having at its outer edge an upwardly bent flange and at the upper edge 55 of the latter a portion extending forwardly and upwardly at an angle to the horizontal plate, said shoe having a long web at the median portion of the shoe and extending from the upwardly bent flange over and considerably beyond the horizontal plate, and bottom chord and top chord members, each chord comprising a pair of horizontally spaced apart timbers, said pairs of timbers extending divergently outwardly, with respect to each other, from the shoe between the horizontal 60 plate and the flange, said web being positioned between and secured to the members of each pair.

2. In a roof truss, a shoe for the truss consisting of a horizontal plate having at its outer edge 70 an upwardly bent flange and at the upper edge of the latter a portion extending forwardly and upwardly at an angle to the horizontal plate, said shoe having a long web at the median portion of the shoe and extending from the upwardly bent flange over and beyond the horizontal 75

plate, said web comprising a pair of adjacently positioned long plates extending with one end through the upwardly bent flange and bent and secured against the outer side thereof, and bottom chord and top chord members positioned at the opposite sides of the web and extending outwardly from the shoe between the horizontal plate and the angular flange.

3. In a roof truss, a shoe for the truss consisting of a horizontal plate having at its outer edge 10 an upwardly bent flange and at the upper edge of the latter a portion extending forwardly and upwardly at an angle to the horizontal plate, said shoe having a long web at the median portion of the shoe and extending from the upwardly bent flange over and beyond the horizontal plate, said web comprising a pair of spaced apart long plates, a filler piece between the web plates, and bottom chord and top chord members, each chord comprising a pair of horizontally spaced 15 apart timbers, said pairs of timbers extending divergently outwardly, with respect to each other, from the shoe between the horizontal plate and the flange, said web being positioned between and secured to the members of each pair.

25 4. In a roof truss, a shoe for the truss consisting of a horizontal plate having at its outer edge an upwardly bent flange and at the upper edge of the latter a portion extending forwardly and upwardly at an angle to the horizontal plate, said shoe having a long web at the median portion of the shoe and extending from the upwardly bent flange over and beyond the horizontal plate, said web comprising a pair of spaced apart long plates extending with one end through the upwardly bent flange and bent and secured against the outer side thereof, a filler piece between the web plates, and bottom chord and top chord members positioned at the opposite sides of the web and extending outwardly from the shoe between the horizontal plate and the angular flange.

30 5. In a timber roof truss, a lower chord member, an arched upper chord consisting of a plurality of sections, each comprising spaced apart timbers placed on edge with the ends of each pair abutted, filler members having their opposite end portions secured between the spaced apart timbers of abutting sections, cross braces secured at their lower ends to the lower chord 35 member and with the upper ends abutting the filler members at the abutted ends of the sections, and metal straps extending over the top and sides of the filler members and secured to the opposite sides of the braces.

45 6. In a roof truss, a shoe for the truss comprising a horizontal plate and a retaining plate disposed at an acute angle relative thereto and joined at its lower edge with the coincident edge of the horizontal plate forming substantially a dihedral angle, the shoe being open at the side opposite the joined portions of the plates, said shoe having a longitudinal web at its median portion extending from the joined portions of the plates, said web extending with one end beyond the joined portions of the plates and bent over and secured against the outer side of the shoe, and bottom chord and top chord members positioned at the opposite sides of the web and extending outwardly from the shoe between the horizontal and angular plates.

50 7. In a roof truss, a shoe for the truss comprising a base plate and a retaining plate spaced thereabove and joined at one edge with the coincident edge of the base plate, the shoe being open 55

5 at the opposite edges of the plates, said shoe having a longitudinal web at its median portion extending from the joined portions of the plates, said web extending with one end beyond the joined portions of the plates and bent over and secured against the outer side of the shoe, and bottom chord and top chord members positioned at the opposite sides of the web and extending outwardly from the shoe between the base and 10 retaining plates.

10 8. In a timber roof truss, a shoe for the truss comprising a base plate and a retaining plate spaced thereabove and joined at one edge with the coincident edge of the base plate, the shoe being open at the opposite edges of the plates, said shoe having a longitudinal web at its median portion extending from the joined portions of the plates, said web comprising a pair of spaced apart long plates; and a bottom chord and a top chord, 15 each comprising a pair of horizontally spaced timbers, said pairs of timbers extending divergently outwardly with respect to each other from the shoe between the base and retaining plates, the plates of the web being positioned between the end portions of the spaced apart timbers of both chords.

20 9. In a timber roof truss, a shoe for the truss comprising a base plate and a retaining plate spaced thereabove and joined at one edge with the coincident edge of the base plate, the shoe be- 25

ing open at the opposite edges of the plates, said shoe having a longitudinal web at its median portion extending from the joined portions of the plates, said web comprising a pair of spaced apart long plates; a bottom chord and a top chord, each comprising a pair of horizontally spaced timbers, said pairs of timbers extending divergently outwardly with respect to each other from the shoe between the base and retaining plates, the plates of the web being positioned between the end portions of the spaced apart timbers of both chords, and a filler piece between the two web plates. 10

15 10. In a roof truss, a shoe for the truss comprising a base plate and a retaining plate spaced thereabove and joined at one edge with the coincident edge of the base plate, the shoe being open at the opposite edges of the plates, said shoe having a longitudinal web at its median portion extending from the joined portions of the plates, a considerable distance beyond the base plate, 20 and a bottom chord and a top chord, each comprising pairs of horizontally spaced timbers, said pairs of timbers extending divergently outwardly with respect to each other from the shoe between the base and retaining plates, said web being positioned between the end portions of the spaced apart timbers of each chord. 25
